UNITED STATES PATENT OFFICE.

JOHN T. SCHAAFF, OF WASHINGTON, DISTRICT OF COLUMBIA, ASSIGNOR TO UNION TYPEWRITER COMPANY, OF JERSEY CITY, NEW JERSEY, A CORPORATION OF NEW JERSEY.

TYPE-WRITING MACHINE.

966,956.

Specification of Letters Patent.

Patented Aug. 9, 1910.

Application filed May 29, 1909. Serial No. 499,230.

To all whom it may concern:

Be it known that I, JOHN T. SCHAAFF, a citizen of the United States, and resident of Washington, in the District of Columbia, have invented certain new and useful Improvements in Type-Writing Machines, of which the following is a specification.

My invention relates to typewriting machines and more particularly to type actions. 10 One of the main objects of the invention is to provide a comparatively simple and efficient type action in which the type basket may receive a case shifting movement.

A further object of my invention is to provide type actions in which there is a substantially uniform leverage throughout the system and in which the leverage of the type bar actuating means remains the same in both the upper and lower case positions of 20 the type basket.

To the above and other ends which will hereinafter appear, my invention consists in the features of construction, arrangements of parts and combinations of devices which will 25 be hereinafter described and particularly pointed out in the appended claims.

In the accompanying drawings wherein like reference characters indicate corresponding parts in the various views, Figure 30 1 is a central, vertical front to rear sectional view of one form of typewriting machine embodying my invention, a sufficient number of parts of the machine being shown to illustrate my invention in its embodiment there- 35 in. Fig. 2 is a vertical transverse sectional view of the same taken on the line α — α of Fig. 1. Fig. 3 is a diagrammatic side view of a type action, the view corresponding to Fig. 1 except that the type bar is shown in 40 the printing position. Fig. 4 is a view which corresponds to Fig. 3 except that the parts are shown shifted for upper case writing.

I have shown my invention applied in the present instance to a front-strike typewriting 45 machine, although it should be understood that the invention from certain aspects may be embodied in other styles of machines.

The frame of the machine comprises a base 1, corner posts 2 and a top plate 3. The carriage 50 is mounted in any suitable manner to travel across the top plate of the machine from side to side thereof, the carriage carrying a cylindrical platen 4 diagrammatically

shown in the drawings. Key levers of the second order 5 are fulcrumed on a pivot wire 55 6 secured at its ends in the base of the machine. The key levers extend forwardly different distances and are provided with finger keys 7 arranged in different banks. Each key lever has an upwardly extending 60 ear 8 to which an angular sub-lever 9 is pivoted at 10. It will be observed that the ears 8 are arranged at different distances along the key levers and at different distances from the fulcrum 6 thereof as are the 65 points of pivotal connection between the key levers and angular sub-levers 9. The purpose of this construction will hereinafter 70 more clearly appear. Each of the angular levers has a rearwardly extending substantially horizontal arm 11, substantially parallel with the associated key lever 5. Each of these arms is slotted or bifurcated horizontally at 12 to receive a fulcrum rod or pin 13 which extends from side to side of the machine and is connected at its ends to upright links 14 pivoted at their lower ends on shouldered pivot screws 15 that are received at their threaded ends 16 in tapped openings in the base of the machine. By mounting 80 the fulcrum rod 13 in the manner described it is adapted to swing on the pivots of the supporting links 14 in a substantially horizontal plane fore and aft of the machine and toward and away from the fulcrum rod 6 85 of the key levers and toward and away from the pivotal connections 10 between the key levers and angular sub-levers. Each of the angular sub-levers has an upright arm 17 bent rearwardly at its upper end as indicated 90 at 18 where it is provided with a laterally extending pin 19 received in an upright slot 20 in an upwardly extending sub-lever 21 of the third order. The sub-levers 21 are all pivoted on a pivot wire 22 and work fore 95 and aft of the machine in slots 23 in a kerfed support 24 secured by upwardly extending arms 25 to a type bar segment 26. The upper ends of the upright sub-levers 21 are bent rearwardly at 27 where they are provided with laterally projecting pins 28 received in inclined slots 29 in the heels of the type bars 30. The type bars are segmentally 100 arranged and mounted on a pivot wire 31 and work in radial slots 32 in the type bar 105 segment 26. The forward ends of the type

bars are supported on a pad 33 which in turn is supported on a segmental strip 34 secured at its ends to forwardly extending arms 35 secured by screws 36 to the type bar segment 26.

Two sets of parallel links 37 are pivotally connected at their forward ends to the segment by shouldered pivot screws 38. The rear ends of these parallel links are connected to rock shafts 39 supported on brackets 40 secured to and depending from the top plate 3 of the machine. Each of these brackets has forwardly extending arms or lugs 41 tapped to receive oppositely disposed screw stops 42 which coöperate with the uppermost of the associated pair of parallel links to limit the movement of the co-operating link and thus limit the case shifting movement of the segment and the type bars carried thereby. Each pair of links 37 is situated near one side of the machine and makes connection with the segment at one end thereof. The left-hand lowermost shift link 37 is extended rearwardly and laterally to form an arm 43 which is connected to a depending link 44 connected to a case shift lever 45 provided with a finger key 46. Each side of the type bar segment has a rearwardly and downwardly extending arm 47 secured thereto by screws 48. These arms are slotted at 49, the slots being inclined and receiving the fulcrum rod 13. It will be understood that the inclined slots 49 form internal cams which coöperate with the fulcrum rod 13 to effect a shifting movement of the fulcrum rod around the pivots 15 of the supporting links 14 when the segment is shifted to change the case position of the types. Thus when the parts are in position to print the lower case types 50, as shown in Fig. 1, the fulcrum rod 13 will be maintained in the position indicated in Fig. 1, whereas when the case shift key 46 is depressed to shift the typebar segment upwardly in order that the upper case types 51 may be brought to the printing point, then the fulcrum rod 13 will be automatically shifted to the position shown in Fig. 4 where it is removed farther from the points of pivotal connection between the angular levers and the key levers. The object of this automatic change of the fulcrum of the angular levers will hereinafter more clearly appear.

From an inspection of Fig. 2 it will be seen that the upright arms 17 of the angular sub-levers all extend to the same heights and make connection with all of said upright levers 21 at the same distance from the fulcrum thereof. It will also be observed that the upright arms 17 of the angular sub-levers are substantially parallel with the upright sub-levers 21 up to the points of connection between the two sets or series of sub-levers. Moreover, it will be seen that the up-

right sub-levers 21 extend varying distances from their fulcrum 22 and extend to progressively greater heights from the center to the sides of the system and that the sub-levers 21 at the sides of the system have laterally extending bends 52, which lateral bends extend inwardly and upwardly from the body portions of the sub-levers to make connection with the associated type bars and to compensate for the difference in width between the system of type bars and the system of key levers. By pivoting the angular sub-levers to the key levers at varying distances from the pivot rod 6 of the key levers in the manner shown, I compensate for the variation in leverage due to the variation in the lengths of the key levers themselves and due to the variation in lengths of the upright sub-levers 21. It will be observed that when the type bar segment is shifted, the sub-levers 21 which are carried by the segment receive a case shifting movement with the type bars, such movement being afforded by the pin and slot connections 19 and 20 between the upright sub-levers 21 and the angular sub-levers 9, which latter are fulcrumed on a part carried by a fixed portion of the machine. It will also be understood that the relative case shift movements between the upright sub-levers 21 and angular levers 9 would ordinarily vary the leverage throughout the system; that is to say, the leverage ordinarily which is provided when the type basket is in the lower case position would be distinctly different from that provided when the type basket is in the upper case position. In order to compensate for this variation in leverage the fulcrum rod 13 is automatically shifted during the case shifting movements of the type basket in the manner hereinbefore described. It will be seen therefore that I have provided a uniform leverage for the parts throughout the system and a uniform dip of the keys and that this uniform leverage and dip is the same whether the type basket be in the upper case position or in the lower case position.

Certain features disclosed herein are claimed broadly in companion application Serial No. 499,228 filed by me of even date herewith, the claims in the present case being restricted to features not disclosed in said other application. There are distinct advantages in the construction disclosed in the present application over that shown in my said application Serial No. 499,228. Thus in the structure of said application Serial No. 499,228, the change in the relation of the two sets of sub-levers effected at the case shifting movements of the parts effects a change in the leverage of the type actions and a change in the dip of the keys throughout the system, whereas in the present construction there is no such change of leverage or change of dip.

Various changes may be made without departing from the spirit and scope of my invention.

What I claim as new and desire to secure by Letters Patent, is:—

1. In a typewriting machine, the combination of a type bar, actuating means therefor comprising a plurality of actuating devices, means for effecting a case shifting movement 10 of said type bar and for effecting a relative movement between certain of said actuating devices during the case shifting movement of the type bar, thereby varying the leverage of said actuating devices, and automatically 15 actuated means for compensating for the variation in the leverage due to variation in the relation of the actuating devices by the case shifting operation.

2. In a typewriting machine, the combination of a type bar, actuating means therefor comprising a plurality of operatively connected levers, means for effecting a case shifting movement of said type bar and for effecting a relative movement between certain of said levers during the case shifting movement of the type bar, thereby varying the leverage of said actuating devices, and automatically 25 actuated means for compensating for the variation in the leverage due to variation in the relation of the levers by the case shifting operation.

3. In a typewriting machine, the combination of a type bar, actuating means therefor comprising a plurality of actuating devices, 30 means for effecting a case shifting movement of said type bar and for effecting a relative movement between certain of said actuating devices during the case shifting movement of the type bar, a fulcrum for certain of said 35 actuating devices, and means for automatically changing said fulcrum to compensate for any variation in the leverage due to variation in the relation of the actuating devices by the case shifting operation.

4. In a typewriting machine, the combination of a type bar, actuating means therefor comprising a plurality of operatively connected levers, means for effecting a case shifting movement of said type bar and for 45 effecting a relative movement between certain of said levers during the case shifting movement of the type bar, a fulcrum for certain of said levers, and means for automatically changing said fulcrum to compensate for any variation in the leverage due 50 to variation in the relation of the levers by the case shifting operation.

5. In a typewriting machine, the combination of a series of type bars, a segment on 55 which said type bars are mounted, a plurality of series of type bar actuating devices, means for effecting a case shifting movement of said segment and for concurrently effecting a relative shifting movement between certain of the type bar actuating de-

vices, thereby varying the leverage of said actuating devices, and automatically actuated means for compensating for the variation in leverage throughout the system due to variation in the relation between said type 70 bar actuating devices effected by a case shifting movement of the segment.

6. In a typewriting machine, the combination of a series of type bars, a segment on which said type bars are mounted, a plurality of series of operatively connected type bar actuating levers, means for effecting a case shifting movement of said segment and for concurrently effecting a relative shifting movement between certain of the type bar 75 actuating levers, a movable fulcrum for certain of said levers, and means for moving said fulcrum to compensate for any variation in leverage throughout the system due to variation in the relation between said levers by the case shifting movement of the segment.

7. In a front-strike typewriting machine, the combination of a shiftable type bar segment, a type bar carried thereby, a key lever, 90 a sub-lever shiftable with said segment and operatively connected with the type bar, a second sub-lever controlled by said key lever, means for operatively connecting said sub-levers to afford a relative shifting movement 95 between them when the type bar segment is shifted, and means for automatically varying the fulcrum of said second sub-lever when the segment is shifted.

8. In a front-strike typewriting machine, 100 the combination of a shiftable type bar segment, a type bar carried thereby, a key lever, an upright sub-lever shiftable with said segment and operatively connected with the type bar, a second sub-lever which is in the 105 form of an angular lever and is controlled by said key lever, means for operatively connecting said sub-levers to afford a relative shifting movement between them when the type bar segment is shifted, and means for 110 automatically varying the fulcrum of said angular sub-lever when the segment is shifted.

9. In a front-strike typewriting machine, 115 the combination of a shiftable type bar segment, a type bar carried thereby, a key lever, a sub-lever shiftable with said segment and operatively connected with said type bar, a second sub-lever controlled by said key lever and connected by a pin and slot connection 120 with said first mentioned sub-lever to afford a relative shifting movement between the sub-levers when the type bar segment is shifted, and means for automatically varying the fulcrum of said second sub-lever 125 when the segment is shifted.

10. In a front-strike typewriting machine, 130 the combination of a shiftable type bar segment, an upwardly and rearwardly striking type bar carried thereby, a key lever of the

second order, an upright sub-lever of the third order pivoted on and shiftable with said segment and operatively connected with said type bar, an angular sub-lever connected by a pin and slot connection with said upright sub-lever to afford a relative shifting movement between the sub-levers when the type bar segment is shifted, and means for automatically varying the fulcrum of said angular lever when the segment is shifted.

11. In a front-strike typewriting machine, the combination of a series of upwardly and rearwardly striking type bars; a shiftable segment on which said type bars are mounted; a series of key levers; and intermediate operative connections between said key levers and type bars, said intermediate connections including a series of sub-levers that vary in length, a second series of sub-levers, one set of the arms of which are of uniform length and the other set of arms of which vary in length to provide a uniform leverage throughout the system, and means for simultaneously varying all of the fulcrums of said second series of sub-levers when the segment is shifted.

12. In a front-strike typewriting machine, the combination of a series of upwardly and rearwardly striking type bars, a shiftable type bar segment on which said type bars are mounted, a series of sub-levers that vary in length, said sub-levers being carried by the type bar segment, a series of key levers, a second series of sub-levers operatively connected to said key levers, one set of the arms of which sub-levers are of a uniform length and the other set of the arms of which vary in length to provide a uniform leverage throughout the system, means for operatively connecting said sub-levers to afford a relative shifting movement between them when the type bar segment is shifted, and means for automatically varying the fulcrums of all of said second series of sub-levers when the type bar segment is shifted.

13. In a front-strike typewriting machine, the combination of a shiftable type bar segment, an upwardly and rearwardly striking type bar carried thereby, a key lever of the second order, an upright sub-lever of the third order pivoted on and shiftable with said segment and operatively connected to the type bar, an angular sub-lever controlled by said key lever, means for operatively connecting said sub-levers to afford a relative shifting movement between them when the type bar segment is shifted, and means for automatically varying the fulcrum of said angular sub-lever when the segment is shifted.

14. In a front-strike typewriting machine, the combination of a series of upwardly and rearwardly striking type bars, a shiftable type bar segment on which said type bars

are mounted, a series of sub-levers that vary in length and which are operatively connected with the type bars and shiftable with the type bar segment, a series of key levers that vary in length, a second series of sub-levers operatively connected to the key levers and to the first mentioned series of sub-levers, one set of the arms of the second series of sub-levers being of uniform length and the other set of arms varying in length according to the variation in length of the first mentioned series of sub-levers and according to the variation in length of the key levers, means for affording a relative shifting movement between said sub-levers when the type bar segment is shifted, and means for automatically varying the fulcrums of all of said second series of sub-levers when the type bar segment is shifted.

15. In a front-strike typewriting machine, the combination of a series of upwardly and rearwardly swinging type bars, a shiftable segment on which said type bars are mounted, a series of sub-levers carried by said segment and connected directly to the type bars by pin and slot connections, a second series of sub-levers connected to the first mentioned sub-levers by pin and slot connections which afford relative shifting movements between the two series of sub-levers when the segment is shifted, key levers to which said second series of sub-levers are connected, and means for automatically varying the fulcrums of said second series of sub-levers when the type bar segment is shifted.

16. In a front-strike typewriting machine, the combination of upwardly and rearwardly swinging type bars, a shiftable segment on which said type bars are mounted, a series of sub-levers of the third order carried by said segment and connected directly with the type bars by pin and slot connections, said sub-levers extending different distances from their fulcrums, a second series of angular sub-levers having upright arms operatively connected to said first mentioned sub-levers to afford relative movements between the two series of sub-levers when the segment is shifted, the upright arms of the angular sub-levers extending a uniform distance from the fulcrums of said angular sub-levers, key levers to which the other substantially horizontally disposed arms of the angular sub-levers are connected at varying distances from the fulcrums of said angular sub-levers, and means for automatically varying the fulcrums of the angular levers when the type bar segment is shifted.

17. In a front-strike typewriting machine, the combination of a series of upwardly and rearwardly striking type bars, a type bar segment shiftable to change the case positions of the types, a series of upright sub-levers shiftable with the segment, a series of

key levers, a series of angular sub-levers intermediate the key levers and upright sub-levers and operatively connected thereto, the angular sub-levers having one set of their arms substantially parallel with the key levers and having the other set of their arms substantially parallel with the upright sub-levers up to the points of operative connection between the angular and upright sub-levers, means for operatively connecting the two series of sub-levers to afford a relative case shifting movement between them when the type bar segment is shifted, and means for automatically varying the fulcrum of said angular sub-levers when the type bar segment is shifted.

18. In a typewriting machine, the combination

of a platen, type bars, actuating means therefor, means for affording a relative case shifting movement between the type bars and platen, and means controlled by the relative case shift between the parts for automatically varying the fulcrums of certain of the type bar actuating means to make the leverage the same in the upper and lower case positions of the parts.

Signed at the borough of Manhattan, city of New York, in the county of New York, and State of New York this 28th day of May A. D. 1909.

JOHN T. SCHAAFF.
